William C. Linton.

UNITED STATES PATENT OFFICE.

CASPER C. BENNETT, OF LOGANSPORT, INDIANA.

DOUBLE-ACTING VALVE.

Application filed February 10, 1927. Serial No. 167,253.

This invention relates generally to improvements in apparatus for flushing toilets and more particularly relates to a double acting valve therefor.

5 It is the primary aim and object of the invention to provide a simple and effective means for flushing a toilet without necessitating the employment of the usual water tanks, the parts being constructed and operated so as to avoid freezing of the water.

More particularly the invention embraces the provision of a flushing apparatus in which the double acting valve and the operating means therefor are constructed as a unit which can be readily inserted between and removed from the junction between the water main and the supply pipe to the bowl.

It is a further object of the invention to provide in a flushing apparatus an auxiliary valve seat for coacting with the valve body for insuring of the main supply of water being directed toward the bowl supply pipe when the toilet is in use and for permitting of the draining of the said bowl supply pipe 25 when the main supply has been closed.

Among the other aims and objects of the present invention is to provide an apparatus of the above character wherein the number of parts is few, the construction simple, the cost of production low and the efficiency high.

Other objects as well as the nature and characteristic features of the invention will be most readily understood from the following description taken in connection with the accompanying drawings and pointed out in the claims forming a part of this specification.

The invention is clearly illustrated in the accompanying drawings in which—

Figure 1 is a side elevation partly in section showing the invention applied to a toilet;

Figure 2 is an enlarged vertical sectional view showing the improved double acting valve and

Figure 3 is an enlarged view partly in section showing the cap and the upper end of the casing.

Similar characters of reference are employed in all of the above described views to indicate corresponding parts.

Referring now more particularly to the drawings, there is provided, a toilet bowl 1 with which communicates a supply pipe 2 leading from a water main 3, a soil pipe 4 being connected with the outlet of the bowl. A seat 4' is pivoted above the bowl and normally is yieldingly held in a raised position through its connection by an arm 5 with the actuating means of the double acting central valve, the latter being actuated for flushing purposes during the time the seat is occupied.

With a view toward reducing the invention to practice the improved double acting valve is connected at the junction between the water main 3 and supply pipe 2 and embodies a chamber in the form of a three way union 6, the lower end being secured to the water main while the horizontal branch is connected by a pipe 7 and elbow 8 to the supply pipe 2. A main or high pressure seat 9 is formed on the inner surface of the union 6 near the lower end while the upper portion is formed with an internal annular shoulder 10 for supporting the auxiliary or low pressure seat member 11. This seat member is in the form of a sleeve, the medial portion of which is restricted and perforated as at 11', the lower edge being bevelled at 12 to form the seat proper while an annular exterior shoulder 13 is formed thereon for engagement with the shoulder 10 so that the auxiliary seat 11 may be supported within the union 6 above the main seat 9. Another union 14 of the threeway type is connected to the upper end of the union 6 and forms part of the main valve chamber, being connected at its horizontal branch with a drain pipe 15 to the sewer.

The valve consists of a body 16 the lower end of which is recessed to receive a washer 17 preferably formed of resilient material such as rubber and this washer coacts with the main seat 9 being releasably secured in the recess by a fastener such as a screw 18 the head acting as a guide to facilitate an effective engagement with the seat 9. The opposite end of the body is bevelled and rounded as at 19 for coacting with the auxiliary seat 12 when the flushing apparatus is in use. The bevelled end of the valve body is also provided with a recess 20 in

which the head 21 of the valve stem 26 is swivelled, connection being maintained by a jamb nut 22.

An elongated pipe casing 24 extends 5 through the flooring or other support for the bowl 1 and is detachably connected to the upper union 14 while also arranged within the pipe casing is another tubular casing 25 housing the actuating rod 23 carrying the 10 valve. The casing 25 is in detachable engagement as by threads 27 with the auxiliary valve seat member 11 while the rod 23 is also in detachable threaded engagement with the adjacent end of the valve stem 26. A suitable 15 closure 28 in the form of a double flanged cap is engaged with the upper ends of the casings 24 and 25. Preferably the inner flange 29 is elongated for slidable engagement with the casing 25 while the outer 20 flange 30 is shorter and interiorly threaded for detachable and adjustable engagement with the casing 24. The cap is apertured to permit sliding of the rod therethrough.

Suitable means such as a coiled spring 31 25 is arranged about the valve actuating rod 23 while the respective ends bear against the under surface of the cap 28 and a collar 32 on the rod, the spring being compressed to depress the rod and normally hold the valve 30 body against the seat 9. The spring also acts to yieldingly hold the toilet seat 4 in a raised position by reason of an adjustable securing element in the form of a nut 33 adjustably engaged on the projecting upper 35 end of the rod 23 and above the loose engagement of the arm 5 with said rod as clearly shown in the drawing.

The operation of the invention may be reviewed as follows:

40 The valve body 16 is operated by the actuating rod 23 and the toilet seat 4 and seats alternately at seat 9 and seat 12. When the toilet seat 4 is depressed the rod 23 is raised by the engagement of the arm 5 with 45 the nut 33 which action also compresses the spring 31 until the bevelled end 19 of the body contacts with the seat 12. During this action water passes from the main 3, through pipes 7 and 2 to the bowl. When the seat 50 is released it is automatically raised by the spring 31 which latter also forces the valve body into engagement with the seat 9. The water in the supply pipe 2 thus flows back into the union or chamber 6, upward through 55 the perforations 11' in the seat member 11 and thence to and through the drain pipe 15.

It is noted that subsequent to the detachment of the nut 33 and cap 28 the unit 60 consisting of the rod 23, valve 16, rod casing 25 and sleeve-like seat member 11 can be removed as a whole from the casing 24. This unit in place seats on the shoulder 10 and is held by the cap 28. The cap 28 also acts as a means for adjusting the tension of the 65 spring 31.

It is believed in view of the foregoing that a further detailed description is unnecessary. Likewise, it is believed that the advantages of the invention will be readily apparent.

I claim:

1. A valve comprising a casing having an inlet opening at one end thereof, a drain opening leading from the opposite end thereof and a discharge opening, a valve seat arranged between said inlet and discharge openings, a detachable sleeve support within said casing arranged between said discharge and drain opening, a valve seat formed with said sleeve, jointly actuated valves for said valve seats having a valve stem, a tubular casing connected to said valve casing, another casing surrounding the valve rod and connected to said sleeve, a cap for detachable engagement with said tubular casing for retaining said sleeve within the valve casing and spring means below said cap associated with the rod for bodily holding said valves upon one of said valve seats.

2. A valve comprising a three-way union 90 having a high pressure valve seat therein, a tubular casing connected to said union and having a drain outlet, a sleeve having a valve seat detachably seated within said union, a tube connected to said sleeve and extending 95 through said tubular casing, a cap secured to said casing for retaining said sleeve and tube therein, a valve rod extending through said sleeve and tube carrying a valve body adapted to coact with said valve seats, and said sleeve having openings therein for establishing communication between said union and the drain outlet within said tubular casing.

3. A valve comprising a main three-way 105 union having a stationary valve seat therein, an auxiliary three-way union connected thereto and having a drain opening, a tubular casing connected to said auxiliary union, a valve seat detachably supported within said main union, a tube connected to said detachable valve seat and extending through said tubular casing, a valve body coacting with said valve seats, a valve rod connected to said valve body and extending through 110 said tube, a cap detachably connected to said tubular casing, a flange formed with said cap and extending about said tube for retaining the detachable valve seat within said main union and a compression spring arranged between said rod and cap.

4. An apparatus of the character described comprising in combination a bowl, a seat therefor, a supply pipe for the bowl, a main three-way union arranged within 120 said supply pipe and having a stationary valve seat therein, an auxiliary three-way union having a drain outlet and connected to the main union, a tubular casing connected to the auxiliary union, a shoulder extend- 130

ing within the main union, a sleeve detachably supported upon said shoulder, and having a valve seat, a valve body coacting with said valve seats, a tube connected to said sleeve, a cap connected to said tubular casting, for holding said tube and sleeve in position, said sleeve having openings therein for establishing communication between the main union and the drain outlet of the auxiliary union, a rod detachably connected to

the bowl seat and operatively connected to the valve body, and spring means arranged between said rod and cap for normally holding the body against the stationary valve seat of said main union and the bowl seat in a raised position.

In witness whereof I have hereunto set my hand.

CASPER C. BENNETT.
